Filed Dec. 29, 1964, Ser. No. 83,206

Term of patent 14 years

(Cl. D26—14)

FIG. 1

FIG. 2

FIG. 3

FIG. 4

FIG. 1 is a front, top and right side perspective view of a combined telephone handset support and equipment housing, showing one form of our new design wherein the front has three pushbuttons and a control wheel;

FIG. 2 is a front elevational view of the form shown in FIG. 1;

FIG. 3 is a top plan view of a combined telephone handset support and equipment housing, showing another form of our new design wherein the pushbuttons and control wheel have been omitted from the front; and

FIG. 4 is a left end elevational view of the form shown in FIG. 3, the opposite end being substantially a mirror image thereof.

The backs of both forms, not shown, are unornamented.

We claim:

The ornamental design for a combined telephone handset support and equipment housing or similar article, substantially as shown and described.
